UNITED STATES PATENT OFFICE.

CARL E. MALMQUIST AND OSKAR H. FREDRICKSON, OF SEATTLE, WASHINGTON.

SIGN.

No. 914,493.

Specification of Letters Patent.

Patented March 9, 1909.

Application filed January 20, 1908. Serial No. 411,751.

To all whom it may concern:

Be it known that we, CARL E. MALMQUIST and OSKAR H. FREDRICKSON, both citizens of the United States of America, and residents 5 of the city of Seattle, in the county of King and State of Washington, have invented certain new and useful Improvements in Signs, of which the following is a specification.

Our invention relates to certain new and useful improvements in signs of the illuminated type and has for its primary object to provide an improvement of this nature which while being comparatively simple in 10 construction and inexpensive to manufacture, embraces certain features which render it very efficient in operation.

With the above and other objects in view, to be referred to as the description progresses, 20 the invention resides in the structural features, combinations and arrangement of parts hereinafter described and succinctly defined in the claims hereto annexed.

Referring now to the accompanying 25 drawing, in which like numerals of reference indicate like parts throughout, Figure 1 is a view in front elevation of one letter constructed in accordance with our invention, parts being broken away, and Fig. 2 is a 30 section taken on line 2—2 of Fig. 1.

Referring now to the drawing by numerals of reference 1 indicates a suitable frame composed of spaced walls 1' and side walls 1" to which spaced walls 1' may be secured 35 in any desired manner. Frame 1 may be of any suitable length and provided with any number of letter openings or openings of other form as will be readily understood, and further if desired only one wall 1' need 40 be formed with said openings. In the present drawing however, we have illustrated a two faced letter frame, which as illustrated, representing the letter "E," is in operation assembled with other letters to constitute 45 the desired subject matter for display.

Reference numeral 2 indicates a reflector, the same consisting of a wall arranged in frame 1 and having its opposite sides or faces polished or painted or otherwise 50 made reflective. Reflector 2 extends entirely across the letter openings in walls 1' and being well spaced from said walls 1' as clearly shown in Fig. 2. Extending from the edges of reflector 2 are walls 3, the same 55 diverging inwardly and being suitably se-

cured to walls 1' about the letter openings thereof so as to confine the light rays. Between the side walls 1" and 3 are provided compartments or spaces 4, for reception of the illuminating means 5, shown as consisting of a number of electric lamps. As now 60 constructed, the desired illumination is obtained by placing one electric lamp approximately midway the length of each side wall 1", said lamps being removably supported 65 in openings in said wall on suitable supports 6 fitted in said openings, whereby said lamps can be removed from frame 1. Walls 3 are provided at their inner edges with openings 7 and said reflector, directly opposite openings 7, is preferably cut out, as at 8, so that the light rays projected through a single opening 7 will strike both sides or faces of the reflector.

Reference numeral 9 indicates hollow fac- 75 ings corresponding in form to the letter openings and fittings thereover. The side walls of facings 9 are provided with flanges 9' through which suitable securing means, as 10, can be passed for securing said facing to 80 walls 1'. Projecting outwardly from the outer walls of facings 9 are flanges 11, which conform in outline to the form of the letter openings and prevent undue spreading of 85 the light rays. Facings 9, are formed of 90 glass or other suitable material so as to be transparent or substantially so so that the illuminating means on the interior of the frame will effect the display of the letters or symbols in a clearly cut manner, without the lamps being seen by the observer.

Having thus described our invention, what we claim as new and desire to secure by Letters Patent of the United States of America, is:

1. In an illuminated sign, a frame having a front wall formed with a letter opening, a rear-facing of glass for the said opening, a rearwardly disposed reflector extending across said letter opening, walls extending from said reflector and secured to said front wall adjacent the edges of said letter opening, said last named walls diverging inwardly and being formed with openings, and illuminating means arranged so that the light rays 100 will be projected through the openings in said last named walls onto said reflector.

2. In an illuminated sign, a frame having spaced walls each formed with a letter opening a reflector arranged in said frame be- 110

tween said spaced walls thereof and being spaced therefrom, inwardly diverging walls extending from said reflector to the spaced walls of said frame and arranged about the letter opening thereof, compartments in said frame to the outer sides of said converging walls, and illuminating means arranged in the compartments of said frame, said diverging walls being formed with openings so that the light rays from said illuminating

means can be projected on opposite sides of said reflector.

Signed at Seattle, Washington this 14th day of January 1908.

CARL E. MALMQUIST.
OSKAR H. FREDRICKSON.
